UNITED STATES PATENT OFFICE.

ISAAC J. MARCUSE, OF RICHMOND, VIRGINIA, ASSIGNOR TO AMERICAN CAN COMPANY,
OF NEW YORK, N. Y., A CORPORATION OF NEW JERSEY.

FRICITION-COVER CONTAINER.

1,161,236.

Specification of Letters Patent. Patented Nov. 23, 1915.

Application filed March 30, 1914. Serial No. 828,139.

To all whom it may concern:

Be it known that I, ISAAC J. MARCUSE, a citizen of the United States, residing in Richmond, in the county of Henrico and 5 State of Virginia, have invented a new and useful Improvement in Friction-Cover Containers, of which the following is a specification.

This invention relates to an improvement 10 in friction cover containers and it consists in constructing the friction cover in such manner that it is provided with an outside hold adapting it to be pried open with a pointed instrument or coin when tightly 15 closed, and an inside hold adapting it to be opened by the fingers when more loosely closed.

In the accompanying drawing which forms a part of this specification Figure 1 20 is a fragmentary elevation of a container provided with a friction cover embodying this invention, the cover being shown tightly closed. Fig. 2 is a complete elevation of the same container and its cover, the latter being shown more loosely closed. Fig. 3 is an 25 enlarged, fragmentary section of the upper part of the container and its cover. Fig. 4 is a top or plan view of the container and cover. Fig. 5 is a perspective view of the 30 container and its cover illustrating the method of removing the cover when the latter is loosely applied, by aid of the fingers only.

In the said drawing A is an ordinary container suitable for baking powder, soda or any similar dry substance. This container is provided at the top with a bead or false wiring a to give a smooth finish and produce a rigid construction. This rigidity is 35 further enhanced by the inwardly projecting bead a^1 , which also forms, inside of the container, a ledge or shoulder to prevent the too deep insertion of the cover, now to be described. The cover B consists of the bottom 40 plate b , the side b^1 and the inwardly formed bead C having the outwardly projecting lip D. The container A may preferably be provided with a side handle E, as the construction of the container is such that after the 45 original contents have been removed, the container may be used as a cup. At the factory when the container is originally filled the cover is put into place and pressed down until its lower edge meets the inner shoulder formed by the bead a^1 which is so

adjusted in position as to leave the lip D of the cover projecting sufficiently above the false wiring edge a of the container, so that a coin or sharp pointed instrument may be inserted beneath the lip to pry up or start 60 the cover. In this condition with the cover thus tightly applied the container as a package may be shipped and sold to the user. The user opens the package by first starting the cover with a suitable prying instrument 65 and thereafter completes the opening by the aid of the fingers alone, the finger hold being the inside of the cover beneath the bead C, as illustrated in Fig. 5 of the drawing. When the package is once opened it can be 70 temporarily closed again tightly enough to protect the contents but yet loosely enough so that the cover can be removed thereafter by the fingers alone.

I claim:—

1. The combination of a container having an inside friction wall, and a cover with an exterior friction wall adapted to engage with the said friction wall of the container, and terminating above its friction wall in an 80 inwardly turned bead extending over the bottom of the cover and shaped to form a finger hold, which bead terminates in an outwardly turned flange arranged above the top edge of the container; whereby the said cover may be pried off by means of the said flange and may be released by grasping beneath the said inwardly turned bead; substantially as specified.

2. The combination of a container having an inside friction wall, and a cover with an exterior friction wall adapted to engage with the said friction wall of the container, and terminating above its friction wall in an 90 inwardly turned bead extending over the bottom of the cover and shaped to form a finger hold, which bead terminates in an outwardly turned flange arranged above the top edge of the container; the said container being formed with an inwardly turned bead 95 below its upper edge which arrests the cover while the flange of the cover is above the top edge of the container; whereby the said cover may be pried off by means of the said flange and may be released by grasping beneath the said inwardly turned bead, substantially as specified.

3. The combination of a container having an inside friction wall and a cover having an exterior friction wall adapted to engage 100

with the said friction wall of the container and terminating above its friction wall in a flange which is turned both inwardly to overhang the bottom of the cover and also 5 outwardly, thereby giving both interior and exterior holds for the removal of the cover; substantially as specified.

Signed and dated at Richmond, Virginia, this 18th day of March 1914, in the presence of two subscribing witnesses.

ISAAC J. MARCUSE.
